FIG. 1 is a front view of a skirt showing my new design as it appears in extended flat position; and

FIG. 2 is a rear view thereof.

The drawing has been lined for color.

The characteristic features of my design reside in the combination on a skirt of two target configurations, one on the front and one on the back with the skirt bottom conforming thereto and with the sides of the skirt being defined by substantially straight lines all as shown in full lines on the drawing.
